Primary Examiner — Cynthia R Underwood(74) *Attorney, Agent, or Firm* — Xsensus LLP(57) **CLAIM**

The ornamental design of a protective case for an electronic device, as shown and described.

DESCRIPTION

FIG. 1 is a front view of the protective case for an electronic device in an open position in accordance with the present invention;

FIG. 2 is a rear view of FIG. 1;

FIG. 3 is a front view of a second embodiment of FIG. 1; and,

FIG. 4 is a rear view of FIG. 3.

The broken lines in the Figures show portions of the protective case for an electronic device that form no part of the claim.
